LOUIS MARX, OF NEW YORK, N. Y.

COMBINED DOLL'S CRADLE AND SOUND-PRODUCING MEANS

Application filed January 28, 1928. Serial No. 250,152.

This invention relates to a combined doll's cradle and sound producing means.

The principal object of my invention comprehends the provision of a cradle for dolls, 5 combined with a sound producing means operative for simulating the cry of a young infant, the sound producing means being associated with the doll's cradle so that a rocking movement of the cradle results in the operation of the sound producing means and in 10 the production of a series of intermittent cries intended for association with a doll receivable by said cradle.

A further prime object of my invention relates to the combination with a doll's cradle of a self-contained sound producing unit which is mounted on the cradle for a bodily movement thereon, the organization of the parts and the mounting of the sound producing unit being such that a rocking action imparted to the cradle produces a bodily movement and operation of said sound producing means.

A still further prime object of the invention resides in the provision of a combined doll's cradle and sound producing means of the voice simulating type or "crier" as it is termed in the art; and an ancillary object of the invention relates to the production of 25 a combined cradle and "crier" unit designed so that standard "criers" may be readily mounted on cradles of standard construction to produce an effective and easily workable combination.

To the accomplishment of the foregoing and such other objects as will hereinafter appear, my invention consists in the elements and their relation one to the other, as herein-after more particularly described and sought 40 to be defined in the claims, reference being had to the accompanying drawings which show the preferred embodiment of my invention, and in which

Fig. 1 is a perspective view of the combined doll's cradle and doll's "crier" of my invention showing a preferred form of combination therebetween,

Fig. 2 is a view thereof taken on an enlarged scale in cross section in the plane of the line 2-2, Fig. 1, and

Fig. 3 is a view thereof taken on an enlarged scale in cross section in the plane of the line 3-3, Fig. 1.

Referring now more in detail to the drawings, I show a preferred embodiment of my invention as comprising a cradle structure generally designated as A and a sound producing unit generally designated as B mounted for bodily movement on the cradle A and operated by a rocking movement of the cradle 55 for producing a simulated crying of a young infant or other appropriate sound to be associated with a doll or similar manikin receivable by said cradle A.

The cradle A may be of any standard design or construction and comprises a bed body 10 mounted for swinging or rocking movement on runners 11, 11. In the construction exemplified in the drawings, the cradle A is made collapsible, the body 10 thereof comprising a rectangular bedstead frame 12 and the head and foot supports 13 and 14 collapsibly mounted on the frame 12. The bedstead frame 12 comprises, in detail 65 a pair of longitudinal members 15 and 16 70 connected together by the crossrods 17, 17 and a pair of rods 18 and 19 attached medially as at 20, 20 to the longitudinal members 15 and 16. The opposite ends of the longitudinal rods 18 and 19 pivotally carry as at 21, 21 the head and foot supports 13 and 14; and the free ends of said longitudinal rods 18 and 19 serve also to resiliently hold the head 75 and foot supports 13 and 14 in set-up or collapsed positions and to act in conjunction 80 with crossrods 22, 22 as a stop means for the set-up limiting position of the fore and rear frame supports 13 and 14.

With this form of cradle construction it will be seen that the cradle may be collapsed 90 by moving the tops of the head and foot frame supports 13 and 14 inwardly towards each other, said cradle being shown in the figures in its set-up condition. While I have shown a collapsible type of cradle embodying 95 the principles of my present invention, it will of course be understood that any other constructional form or design of doll's cradle may be employed.

The sound producing means B comprises 100

a self-contained unit mounted on the cradle A so that a rocking movement of the cradle produces the bodily and operative movement of the sound producing unit. This sound producing unit B is preferably of the type used in the art for producing a simulated crying of an infant and known as a "mama voice" or "crier". The invention contemplates the combination and joinder of standard forms of "crier" units with any of a number of standard forms of cradle constructions in a manner to permit an effective mechanical association therebetween to produce an efficiently organized and easily operated assembly.

The sound producing unit B more specifically comprises a "crier" including a tubular casing 23 made, for example, of ordinary cardboard mailing tube, a perforate sheet metal wall 24 at one end thereof and an imperforate sheet metal wall 25 at the other end thereof, the sheet metal wall 25 defining a cover for the casing 23 and also an airtight cover for one end of a collapsible bellows bag 26 which may be made of a rubberized fabric or the like, the other end of the bellows bag being closed by a weighted member 27 and a cover section 28, the said bellows bag 26 being clamped airtight between the weight 27 and the cover 28, as clearly shown in Fig. 2 of the drawings. A sound producing element in the form of a reed 29 is provided, and this reed is preferably attached to the cover section 28 and arranged over an aperture 30 therein, which aperture together with an orifice 31 in the weight 27 forms the communicating means between the bellows chamber and the outer sound chamber of the sound producing unit. In this form of "crier" unit, movement of the unit between erect and inverted positions causes an alternate distending and collapsing of the bellows bag 26 responsive to the gravitational movements of the weight 27, and this results in the production of a series of intermittent sounds or cries simulating the voice of a young infant.

The sound producing unit B is mounted on the cradle A so that the operating movements may be imparted to the sound producing unit when the cradle is rocked; and preferably operating means are employed which produce an oscillatory movement in said sound producing unit greater in amplitude than that of the swinging arc of said cradle and sufficient to effectively operate the said sound producing unit. The mounting of the unit B on the cradle A is also such as to prevent interference with the normal functions of the bedstead of the cradle.

To these ends the unit B is provided with side straps 32, 32 affixed to the top and bottom cover walls 24 and 25 of the unit and to the said straps are attached the spindles 33 and 34 which are journaled in holders 35 and

36 made of sheet metal or the like and constructed so that the same may be fitted over and held by adjacent crossrods 17, 17, as clearly shown in the figures of the drawings. The unit B is so mounted that normally, as shown in Figs. 1 and 3 of the drawings, it lies with its axis in a horizontal plane. The unit B is thus mounted for bodily oscillation in the attachable and detachable holders 35 and 36.

For operating the sound producing unit B in response to the rocking movements of the cradle, I provide, in the preferred construction, a depending arm 37 weighted at its bottom as at 38 and pivotally connected at 39 to an arm 40 fixed to one of the spindles such as 34. The weighted end 38 of the arm 37 is intended for contacting engagement with the floor or other support on which the cradle is mounted, as clearly shown in Figs. 2 and 3 of the drawings.

With this recited construction it will be seen that when the cradle A is rocked in the direction shown by the arrow 41 in Fig. 2 of the drawings, the weighted end 38 of the arm 37 engages the floor or other support and tilts the sound producing unit B from its normal horizontal position to a position such as shown in Fig. 2 of the drawings sufficient to permit the weight 27 thereof to move to bellows distending position. When the cradle is moved, however, in the reverse direction, as shown by the arrow 42 in Fig. 2 of the drawings, the weight 38 of the operating arm 37 disengages the floor and gravitates to move the sound producing unit B in the opposite direction sufficient to permit the weight 27 thereof to move to a bellows collapsing condition. It will be understood that the collapsing of the bellows results in sounding the reed 29 of the unit B, the sound being emitted through the communicating orifices 30 and 31 and the apertured cover 24. It will be noted that the mounting of the unit B and its operation are such as to minimize interference with the positioning of the mattress or similar article on the bedstead 12, and so that an oscillatory or swinging movement is given to the unit B which is preferably greater in amplitude than that of the swinging arc of the cradle in order that the sound producing unit B may be made to function for greater efficiency.

The manner of making and operating the combined cradle and sound producing apparatus of my present invention will, in the main, be fully apparent from the above detailed description thereof. It will be further apparent that I have provided a combined cradle and "mama voice" or "crier" designed so that standard "criers" may be readily attached to cradles of standard construction to produce an effective and easily workable combination. It will be further seen that the "crier" unit may be mounted for quick and

convenient accessibility and as an integral unit detachably attachable to the cradle and normally forming an integral part thereof.

It will also be apparent that while I have shown and described my invention in the preferred form, many changes and modifications may be made in the structure disclosed without departing from the spirit of the invention, defined in the following claims.

I claim:

1. In combination, a doll's cradle comprising a bed body mounted for rocking movement; and a doll crier comprising a self-contained sound producing unit mounted for bodily sound producing movement on said cradle, said self-contained sound producing unit comprising a casing and sound producing means all contained within said casing, and means for operating the sound producing unit when the said cradle is rocked, said means including mechanism for imparting to said sound producing unit an arcuate movement greater in amplitude than that of the swinging arc of said cradle.

2. In combination, a doll's cradle comprising a bed body mounted for rocking movement; and a doll crier comprising a self-contained sound producing unit oscillatably mounted for bodily sound producing movement on said cradle, said self-contained sound producing unit comprising a casing and sound producing means all contained within said casing, and means for oscillating the sound producing unit when the said cradle is rocked, said means including mechanism for imparting to said sound producing unit an oscillatory movement greater in amplitude than that of the swinging arc of said cradle.

3. In combination, a doll's cradle comprising a bed body mounted for rocking movement; and a doll crier comprising a self-contained sound producing unit mounted for oscillatory bodily sound producing movement on said cradle, said self-contained sound producing unit comprising a casing and sound producing means all contained within said casing, and means for operating the sound producing unit when the said cradle is rocked, said means including a device connected to said unit and having a point of engagement with the floor or other support upon which the cradle is rocked whereby the engagement and disengagement of said device with said support when said cradle is rocked effects the sound producing movements of said sound producing unit.

4. In combination, a doll's cradle comprising a bed body mounted for rocking movement; and a doll crier comprising a self-contained sound producing unit oscillatably mounted for bodily sound producing movement on said cradle, said sound producing unit comprising a casing, a bellows therein,

a reed associated therewith and a weight movable in said casing and operating the bellows to sound the reed; and means for operating the sound producing unit when said cradle is rocked, said means including devices for imparting to said sound producing unit a swinging movement greater in amplitude than that of the swinging arc of said cradle, the swinging movement imparted to said unit being sufficient to effect an oscillating movement of said weight in said casing to produce a series of sounds when said cradle is rocked.

5. In combination, a doll's cradle comprising a bed body mounted for rocking movement, a sound producing unit mounted on said cradle, and means for operating the sound producing unit when said cradle is rocked, said means including mechanism for imparting to said sound producing unit a movement greater in amplitude than that of the swinging arc of said cradle.

6. In combination, a doll's cradle comprising a bed body mounted for rocking movement, a self-contained sound producing unit mounted on said cradle for oscillating movement as a unit relative to the body of said cradle, and means for oscillating the sound producing unit by or independent of the rocking movement of the cradle.

7. In combination, a doll's cradle comprising a bedstead and head and foot supports mounted for rocking movement; and a doll crier comprising a self-contained sound producing unit swingably mounted on said bedstead with its axis arranged horizontally, said self-contained sound producing unit comprising a casing and sound producing means all contained within said casing, and means for operating said sound producing unit to opposite sides of its horizontal position by a rocking movement of the cradle.

Signed at New York in the county of New York and State of New York this 12th day of January, A. D. 1928.
